UNITED STATES PATENT OFFICE.

HERMAN IHLENBURG, OF PHILADELPHIA, PENNSYLVANIA, ASSIGNOR TO
THE MACKELLAR, SMITHS & JORDAN COMPANY, OF SAME PLACE.

DESIGN FOR TYPE.

SPECIFICATION forming part of Design No. 16,917, dated September 28, 1886.

Application filed August 27, 1886. Serial No. 212,024. Term of patent 3½ years.

To all whom it may concern:

Be it known that I, HERMAN IHLENBURG, (assignor to the MACKELLAR, SMITHS & JORDAN COMPANY,) of the city and county of Philadelphia, Pennsylvania, have invented and produced a new Design for a Font of Printing-Type, of which the following is a specification.

The nature of my design is clearly shown in the accompanying typographic impression, to which reference is made; and it consists of an unshaded oblique letter, the up-and-down portion sloping or inclining from right to left, while the cross portions of the letter slope or incline from left to right. The central line of the A and H is inclined, extended upon the left, and provided with the short curved line with dot termination. The curved line with dot termination is found in the C and G at the base of an inclined line extending downward from the upper right-hand portion of the letter. The upper rounding portion of the B, D, P, and R is extended above and upon the left of the up-and-down portion, as shown. The inclined central line of the E and F has the curved line with dot termination upon the right hand and left hand, and this curved line with dot termination is found in the R, S, and Z, as shown.

The character of the design is preserved in the lower-case, notably the h, i, l, m, n, r, and z, and in the numerals, notably in the 1, 2, 4, and 7.

z, and in the numerals, notably the 1, 2, 4, and 7.

I claim as new—

The design for a font of printing-type, as shown and described, the same consisting of an unshaded oblique letter, the up-and-down portion sloping or inclining from right to left, the cross portion sloping or inclining from left to right, the central line of the A and H inclined, extended upon the left, and provided with the short curved line with dot termination, the C and G having an inclined line extending from the upper right-hand portion and provided with the curved line with dot termination, the upper rounding portion of the B, D, P, and R extended above and upon the left of the up-and-down portion, the inclined central line of the E and F having the curved line with dot termination upon the right hand and left hand, and the curved line with dot termination found in the R, S, and Z, as shown, and the character of the design preserved in the lower-case, notably in the h, i, l, m, n, r, and z, and in the numerals, notably in the 1, 2, 4, and 7.

HERMAN IHLENBURG.

In presence of—

C. F. HUCH,
HERMAN METIUS.
